VEHICLE WIND DEFLECTOR

John A. Bott, 931 Lake Shore Drive,
Grosse Pointe Shores, Mich.

Filed Nov. 17, 1964, Ser. No. 82,656

Term of patent 14 years

(Cl. D14—6)

FIGURE 1 is a perspective view of a vehicle wind deflector showing my new design; the vehicle and mounting bracket shown in broken lines being included for illustrative purposes only;

FIGURE 2 is a diametrical cross sectional view thereof;

FIGURE 3 is a diametrical cross sectional view of a modified form of the vehicle wind deflector shown in FIGURES 1 and 2;

FIGURES 4 and 5 are plan and elevational views of the wind deflector shown in FIGURES 1 and 2; and

FIGURE 6 is an enlarged fragmentary plan view of the wind deflector shown in FIGURE 3.

I claim:

The ornamental design for a vehicle wind deflector, substantially as shown and described.
